CLAIM

The ornamental design for a cutlery storage container, as shown and described.

DESCRIPTION

FIG. 1 is a top, front perspective view of a cutlery storage container, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another top, front perspective view thereof; and,

FIG. 9 is a top, front perspective view thereof, shown in closed condition.

The broken lines in the figures illustrate the portions of the cutlery storage container that form no part of the claimed design.
